UNITED STATES PATENT OFFICE.

NELSON C. BLAKE, OF WOONSOCKET, RHODE ISLAND.

PICKER-STICK CHECK.

Application filed June 14, 1922. Serial No. 568,284.

To all whom it may concern:

Be it known that I, NELSON C. BLAKE, a citizen of the United States, residing at Woonsocket, in the county of Providence and State of Rhode Island, have invented 5 certain new and useful Improvements in Picker-Stick Checks, of which the following is a specification, reference being had to the accompanying drawings.

10 This invention relates to loom attachments, and particularly to picker stick checking devices.

The general object of my invention is to provide means for retarding the movement 15 of the picker stick at the end of its stroke so as to avoid any bending or hammering of the same when in action and to prevent any rebound of the picker stick and hold it medially disposed with relation to the 20 lay beam.

A more particular object of this invention is to provide a picker stick check of a very simple and yet thoroughly effective character which may be easily applied to 25 looms, has few parts, and is cheaply constructed.

My invention is illustrated in the accompanying drawings, wherein:—

Figure 1 is a side elevation of a portion 30 of a loom showing the ordinary picker stick motion and showing my improved picker stick check applied thereto;

Figure 2 is an under side plan view of one end of the lay beam showing the check 35 applied thereto, the picker stick being in section;

Figure 3 is a fragmentary view of the upper end of the picker stick;

Referring to these drawings, it will be 40 seen that I have illustrated the ordinary picker stick and operating mechanism of a loom, this mechanism comprising the lay beam 10 slotted, as at 11, to permit the oscillation of the picker stick mounted upon the 45 supporting upright or sword 12 which is operatively connected to the usual picker stand 13. Rocking upon the upper face of this stand is the usual or conventional shoe 14, and engaged with this shoe is the picker 50 stick 15. The picker stick is illustrated as passing through a slot in the shoe and into a slot 16 in the stand. The shoe 14 has the usual grooved, upwardly extending portion 17 wherein the tongue 18 is disposed, which 55 extends down through the slot in the shoe and into the slot 16, this tongue being

grooved to receive the lower end of the picker stick and the picker stick and tongue being held together by a bolt 19.

Attached to the face of the picker stick 60 is the strap 20 which passes downward over the outer face of the picker stick and over the curved lower end of the picker stick and then passes to and around the spring retracted roller 21. All of these parts are 65 of the usual and ordinary construction.

Attached to the under face of the lay beam at each end is a plate 22^a carrying a downwardly projecting bracket 22 which is longitudinally slotted at a plurality of 70 points, as at 23. Engaged with the bracket is an approximately U-shaped iron 24 having stud bolts 25 or equivalent devices extending laterally outward from one arm of the member 24 and through the slots 22, 75 these stud bolts being held in adjusted position by means of the nuts 26. Attached to the inner faces of the two arms of the member 24 are a pair of inwardly convergently disposed leaf springs 27, the inner faces of 80 which are faced with leather 28. These springs are held in place upon the outer ends of the arms by means of the rivets 29.

I have only illustrated one end of the lay beam with one picker stick and the corresponding check, but it will be understood that both ends of the lay beam are similarly constructed and provided with a similar picker stick and check. The picker stick is, of course, embraced by a leather band 30 for that portion of the picker stick which enters the check so that the leather band will come in contact with the leather facings 28 of the check device. I am aware that checks for picker sticks have included 85 oppositely disposed, resiliently supported checking members, but devices of this kind as known to me have been relatively complicated and very liable to get out of order. This device of mine is very simple and it can be readily repaired or replaced at any time. The stick is gently checked upon its backward movement, but as it moves rearward the springs exert a greater checking 90 action and greater friction so that the picker stick is stopped without jar or shock. While I have illustrated the check as disposed at the outer end of the slot 11, it will be understood that two checks of the 95 same character might be used at the inner and at the outer end of the slot but check the picker stick at both ends of its stroke.

My device may be used either for the right or left of the machine and is adjustable either forward or backward. The check is particularly small and cheap and yet thoroughly effective. There is nothing to wear out and it can be taken off and put on in a few minutes, which causes the picker stick to travel straight and does not let the picker stick rebound but holds the picker stick firm and lets the picker stick go straight when throwing the shuttle.

I claim:

A picker stick checking attachment for looms comprising a plate having a bracket carried thereby and adapted to be attached

to the under face of a lay beam, the bracket being longitudinally slotted at a plurality of points, a U-shaped member formed to provide two parallel arms and having bolts extending from one of said arms and extending through the slots in the bracket, and springs riveted at their forward ends to the forward ends of the arms and extending rearwardly and in convergent relation, the inner faces of said springs being covered with leather.

In testimony whereof I hereunto affix my signature.

NELSON C. BLAKE.
